UNITED STATES PATENT OFFICE.

FELIKS BARNIAK, OF ROSEMONT, WEST VIRGINIA.

RAILROAD-TIE.

1,345,572.

Specification of Letters Patent.

Patented July 6, 1920.

Application filed May 7, 1920. Serial No. 379,535.

To all whom it may concern:

Be it known that I, FELIKS BARNIAK, a citizen of Poland, residing at Rosmont, in the county of Taylor and State of West Virginia, have invented certain new and useful Improvements in Railroad-Ties, of which the following is a specification.

The primary object of the invention is the provision of a metallic supporting tie for railway rails that is exceedingly simple in construction, well braced and possesses great strength, the rails being readily secured thereon in track formation.

A further object of the invention is the provision of a metallic railway tie easily and inexpensively manufactured from I-beams of suitable proportion, bracing means being provided forming chair portions thereon for ready attachment of the rails in transverse position.

A still further object of the invention is to provide a metallic tie requiring only the provision of a plurality of identical braces in its construction, the railway rails being readily mounted and secured thereon.

With these general objects in view, the invention consists of the novel combination and arrangement of parts hereinafter more fully described in connection with the accompanying drawing and in which like reference characters designate corresponding parts throughout the several views.

In the drawing,

Figure 1 is an elevational view of my tie with rails mounted thereon illustrated in transverse section,

Fig. 2 is a top plan view thereof,

Fig. 3 is a side elevation of the same partially broken away, and

Fig. 4 is a perspective view of one of the brace members employed in the manufacture of the tie.

My invention broadly consists of a metal I-beam having a web 10 and top and base flanges 11 and 12 substantially double the width of the height of said web 10 whereby railway rails such as 13 may be seated for support upon the top flange 11 accurately spaced apart according to the gage of the road. A plurality of braces or brackets 14 are placed in pairs at opposite sides of the web 10 spaced from the opposite ends of the I-beam forming chair portions of the tie bracing the I-beam at these points where the rails 13 are positioned when the tie is in use.

The braces 14 have right angular portions 15 and base flanges 16, for seating upon the base 12 of the I-beam contacting the web 10 thereof for the transverse positioning of securing bolts 17 through said web 10 and the brackets 14 at the opposite sides thereof. Upwardly and outwardly extending terminal portions 18 of the brackets 14 of ogee curvature with substantially horizontal end portions 19 contact the lower face of the top flange 11 of the I-beam for strengthening and bracing the same. The upper and lower end faces 20 and 21 of the braces 14 are flush with the outer edges of the top flange 11 and base flange 12 of the I-beam when the device is assembled and a strong tie is provided upon which the rails 13 are readily secured in planes above and between the sets or pairs of braces 14 positioned as heretofore described.

Angular securing plates 22 adapted for seating transversely upon the top flange 11 of the tie overlying the base flanges of the rails 13 are secured in position by hold-fast devices such as stub bolts 23 extending through perforations 24 in the plates 22, similar perforations 25 in the top flange 11 of the tie and threaded into perforations 26 of the bracket end portions 19. A strong and economical tie is provided formed solely of an I-beam braced and strengthened by the brackets 14 at chair or supporting portions adjacent the opposite ends of the beam for mounting railway rails 13 thereon in track formation. The curved portions 18 of the brackets 14 not only strengthen the tie, but afford slight resiliency for the chair portions thereof, it being understood that the tie is mounted upon or embedded in the roadbed in substantially the usual manner. While the form of the invention herein set forth is believed preferable, it will nevertheless be understood that minor changes may be made therein without departing from the spirit and scope of my invention.

What is claimed as new is:

1. A railway tie comprising an I-beam having the top and base flanges connected by a central web, angular braces secured in pairs to the web in spaced relations inwardly of one end thereof forming a chair portion with the end portions of the braces flatly contacting the opposite inner faces of said top and base flanges, the upper end portions of the braces having threaded perforations

and the top flange of the I-beam having perforations in alinement therewith adapted for the reception of holdfast devices and rail engaging plates transversely of the top flange of the beam provided with perforations in alinement with said perforations of the beam and stub bolts adapted to be secured through said alining perforations when a rail is positioned for use beneath said plates.

2. A tie comprising an I-beam having an upright web, brackets arranged in pairs at opposite sides of the beam with right angular portions coincident with the base flange of the beam and the adjacent portion of the web, securing bolts through the web of the beam and the adjacent portions of the brackets, the latter having double curved upwardly and outwardly projecting portions terminating in supporting arrangement beneath the outer edge portions of the top flange of the beam and rail holding means positioned

through the top flanges of the beam and the adjacent end portions of the brackets.

3. A tie comprising an I-beam having an upright web, brackets arranged in pairs at opposite sides of the beam with right angular portions coincident with the base flange of the beam and the adjacent portion of the web, securing bolts through the web of the beam and the adjacent portions of the brackets, the latter having double curved upwardly and outwardly projecting portions terminating in supporting arrangement beneath the outer edge portions of the top flange of the beam, angular rail securing plates transversely mounted upon a top flange of the beam above the upper end portions of the opposite brackets and securing bolts through said plates and top flange of the beam threaded into the upper end portions of the brackets beneath said top flange.

In testimony whereof I affix my signature.
FELIKS BARNIAK.
